UNITED STATES PATENT OFFICE.

HENRY K. HUPPERT, OF SAN FRANCISCO, CALIFORNIA.

RADIOTUBE.

Application filed June 11, 1924. Serial No. 719,440.

This invention relates to improvements in radio tubes.

The principal object of this invention is to provide means for greater control of the 5 electronic flow.

Another object is to provide a tube where- in alternating current may be employed for the lighting of the filaments.

10 Another object is to provide a tube having a greater plate surface.

Another object is to provide a double filament with a result that if one filament burns out the tube will still function with the remaining filament.

15 Other objects and advantages will be apparent during the course of the following description.

In the accompanying drawings forming a part of this specification, and in which 20 like numerals are employed to designate like parts throughout the same:—

Figure 1 is a vertical cross section of a tube constructed in accordance with my invention,

25 Figure 2 is a cross section of the tube taken on the line 2—2 of Figure 1,

Figure 3 is a bottom plan view of the tube,

Figure 4 is a diagrammatic arrangement 30 showing the employment of a transformer employing alternating current for lighting the filaments,

Figure 5 discloses a diagrammatic arrangement of the standard form of filament, disclosing the electronic losses, and

35 Figure 6 is a detail perspective view showing one-half of my improved plate construction.

Radio tubes employ a heated filament for 40 the purpose of causing an electron flow and up to the present time, as far as applicant is aware of, it has been impossible to satisfactorily employ alternating current for heating filaments without the use of external apparatus, due to the fact that a decided

45 hum would be produced by an alternating current and amplified in the customary manner by the action of the tube. Applicant has devised a tube which permits the use of an alternating current without the objectionable features referred to and also receives greater electron control and by referring to the drawings it will be noted that the numeral 5 designates the customary

50 glass bulb and the numeral 6 the metal base 55 adapted to support the bulb. The base is held to the bulb by a plastic composition as

shown at 7, while a porcelain insulator 8 is held within the base by an annular ring 9. This base supports four prongs designated at 11, which prongs are customary in all 60 tubes. These prongs form the leads to which the elements of the tube are connected.

A support 12 is sealed to the base of the tube 5 which has mounted therein the tube 65 elements. It is, of course, understood that the tube is evacuated in the usual manner.

Referring to Figure 6, it will be noted that I have provided a plate 13 which consists of two semi-circular plates 14 and by 70 referring to Figure 2, it will be noted that two of these plates are employed the same being secured together so as to form barrels, and hereinafter the plate will be referred to as a double barrel structure.

At 16 and 17, I have shown wires for the double barrel structure which wires are secured thereto and have their lower extremities sealed in the support 12. The wire 16 has a lead 18 connected thereto, which lead 80 extends downwardly and is connected to one of the prongs 11.

Mounted within the barrels are grids 19 and 21, which grids are formed in the usual manner and are supported by rods 22 and 85 23, respectively. The lower end of the rod 22 being bent downwardly and sealed in the support 12. The rod 23 is also sealed in the support 12 and is connected by a lead 24 to one of the prongs 11.

At 26, I have shown a U-shaped wire connecting the upper ends of the supports 22 and 23, which in effect join the grids 19 and 21. Filaments 27 and 28 are arranged so as to extend throughout the length of the grids 95 19 and 21, respectively, which filaments have their upper extremities supported by a Y 29, which Y is, in turn, mounted upon a rod 31 extending downwardly into the support 12. This rod is connected by a lead 32 to the 100 shell 6. The lower extremity of the filaments 27 and 28 are connected to wires 33 and 34, respectively, which wires are sealed to the support 12 and are connected by the leads 36 and 37 to the remaining prongs 11. 105

The structure thus described completes the structure of my improved tube. By referring to Figure 4, I have diagrammatically represented the filaments of the tube at A and B, the Y connection at C between the 110 leads D and E, which correspond to the leads 36 and 37 of Figure 1, I connect the second-

ary F of a transformer and to the neutral point G I connect a lead H. At I, I have shown an electrical connection between C and H, which connects the zero potential 5 point of the transformer to the zero potential of the filament.

The purpose of the conductor "I" is two-fold. In the first place should one of the filaments, either "A" or "B" burn out, the 10 conductor "I" will form the return lead. Also the conductor may be considered as being used in place of a potentiometer and acts as the same in conjunction with the received signal, thereby eliminating the A-C 15 hum, which would, otherwise, be present. Experiments have proven that when the conductor "I" is severed a hum immediately commences in the circuit.

At J I have shown the primary of a 20 transformer which receives its energy from any suitable alternating source of electrical current. It is possible to secure greater electron control, than is possible with the usual forms of tube having the hair-pin 25 filament, because in my tube the filaments are entirely surrounded by a grid and a plate, a condition which does not exist in the usual form of tube and by referring to Figure 5 it will be noted that there is no 30 plate or grid to entirely surround the filaments, therefore space between the dotted lines represents a loss and by referring to Figure 5 it will be seen that this space 35 comprises a considerable area, substantially the area between the points C—D and A—B, therefore, it will easily be seen that it is impossible to control electronic action between the dotted lines of Figure 5, while with the 40 double barrel construction the plates entirely surround the grid and the filaments, with the resulting increased efficiency.

It is possible with my tube to short the two prongs 11 to which the filament leads are connected and use the shell for the re-

turn of the current, with the result that 45 the tube will function on one-half the voltage that is required when the filaments are in series, an increased electron emission will result.

It will thus be seen that I have devised a 50 tube having all of the advantages above set forth.

It is to be understood that the form of my invention herewith shown and described is to be taken as a preferred example of the 55 same, and that various changes in the shape, size and arrangement of parts may be resorted to without departing from the spirit of the invention or the scope of the subjoined claim. 60

Having thus described my invention, I claim:

A radio tube comprising a base, a bulb mounted on said base, a support mounted in said bulb, a plurality of prongs secured to said base, leads extending from said prongs and said base and terminating in said support, a plate mounted on said support, said plate being shaped so as to form two parallel barrel-shaped structures, means for electrically connecting said plate to one of said leads in said support, a grid centrally positioned in each of said barrels and mounted above said support, means for connecting said grids in series, means for electrically connecting said grids with another of said leads, in said support, a filament centrally positioned in each of said grids, the lower extremity of said filaments being electrically connected to two of said leads 80 in said base, the opposite end of said filaments being connected by a Y shaped conductor, and means for electrically connecting the center of said Y shaped conductor with the remaining lead in said support. 85

In testimony whereof I affix my signature.

HENRY K. HUPPERT.
